UNITED STATES PATENT OFFICE.

WILLIAM SCHILLING, OF NEW ORLEANS, LOUISIANA.

HAND-LOOM.

SPECIFICATION forming part of Letters Patent No. 276,478, dated April 24, 1883.

Application filed May 9, 1882. (No model.)

To all whom it may concern:

Be it known that I, WILLIAM SCHILLING, a resident of New Orleans, in the parish of Orleans and State of Louisiana, have invented a 5 certain new and useful Improvement in Hand-Looms; and I do hereby declare the following to be a full, clear, and correct description of the same, reference being had to the annexed drawings, making a part of this specification.

10 My invention consists in the novel combination and arrangement of parts, as will be hereinafter more fully set forth and specifically claimed.

15 The annexed drawings clearly illustrate my improvements.

Figure 1 represents a longitudinal section of a loom with my improvements applied thereto. Fig. 2 is a similar view, but with the heddles in different positions. Fig. 3 is a detail showing 20 a front view of the lay and picker-sticks, with a portion of the loom-frame.

In the drawings, the letter A designates an ordinary loom-frame, provided with a warp-beam, B, heddles C, operating-levers C' M' M 25 and their respective shafts a² and b', and usual cord-connections, a cloth-beam, F, with ratchet-wheels f f', lever f², and pawls f³ f⁴ for operating and holding said cloth-beam, and guide-rails H k k' L and tension-bars I I' for the 30 warps. These parts are all substantially such as have been heretofore employed.

My improvements will now be understood by referring to the drawings, whereon the letter D represents the batten or lay carrying the 35 reed D^o. This lay is composed of a beam, d', having a V-shaped under edge, the outer ends of which rest or operate on slotted metallic plates d², having longitudinal slots therein, which are secured over recessed portions of the 40 upper longitudinal side pieces of the loom-frame. The slots in the plates d² and recesses in the side pieces are made to receive the shanks and heads of bolts E, which also pass through the beam d', and which are provided 45 with nuts e, the tightening of which will reduce the stroke of the lay, or securely lock the same in a vertically-suspended position. The aforesaid beam d' is provided with vertical slots for the reception of a pair of hangers, d³, 50 having perforations therein for pins d', which

afford means for adjusting and holding the same at different heights. On these hangers are loosely fitted transverse bars d⁵ d⁶, having grooved inner edges for receiving and holding the upper and lower cross-bars of the reed D^o. 55 These parts are held on the hangers by pins inserted in perforations made in the lower ends of said hangers, so that the bar d⁶ shall rest thereupon, as shown at d⁷. The upper surface of bar d⁶ constitutes the race in which 60 the shuttle travels.

At a short distance inside of each hanger is pivoted, by pins e', to the front edge of the beam d' a pair of links, e, having slotted outer ends, in which the picker-sticks P are adjustably 65 held by pins e¹².

The picker-sticks are operated by means of a handle, e², and cords e³ e⁴, which are suspended from the beam d', as shown in Fig. 3, and which have side connections with the 70 picker-sticks, as shown at e⁵ e⁶.

In order to limit the stroke or throw of the picker-sticks, they are connected by strings of suitable lengths with their adjacent hangers, as shown at e⁷ and e⁸. 75

The operation of my improved loom is as follows: The weaver, after taking his seat, pushes back one of the picker-sticks to the end of the race. He next places the shuttle in the box in front of the said picker-stick, and 80 then depresses with his foot a lever, M, so as to raise the heddle connected therewith, thus forming an opening or shed in the warp, when by jerking the handle e² he causes the aforesaid picker-stick to drive the shuttle through 85 the said shed and into the shuttle-box at the opposite end of the race, striking in its course and carrying with it the opposite picker-stick. Then he draws the lay toward him, which 90 brings with it, in front of the reed, the weft-thread. Next he operates one of the other levers M, and through it the harness connected therewith, which opens a new shed. Then he pushes the lay from him and drives the shuttle back to the first end of the race. The lay 95 is next drawn forward, so as to push the weft-thread against the last thread, and thus the operation is continued to produce the desired material.

The bolts E and nuts e afford means for 100

limiting the stroke of the lay, as well as for securely locking the said lay when the loom is not required for operation.

Having described my invention, what I claim as new, and desire to secure by Letters Patent, is—

The lay carrying a reed, shuttle-race, and picker-sticks, the supporting-beam of said lay having its ends provided with bolts and nuts, so as described, in combination with the frame

having recessed portions, and the slotted plates d^2 , that are secured over the recesses in such frame, substantially as and for the purpose specified.

In testimony whereof I hereunto sign my name.

WILLIAM SCHILLING.

In presence of—

BEN. ARMBRUSTER.

J. C. HUBBELL.
